DESIGN FOR A RANGE

Carl H. Hoffstetter and Robert F. Hoffstetter,
Erie, Pa.

Application October 31, 1936, Serial No. 65,627

Term of patent 7 years

To all whom it may concern:

Be it known that we, Carl H. Hoffstetter and Robert F. Hoffstetter, citizens of the United States, residing at Erie, in the county of Erie and State of Pennsylvania, have invented a new, original, and ornamental Design for a Range, of which the following is a specification, reference being had to the accompanying drawing, forming part thereof, and in which drawing: Figure 1 is a perspective view of a range showing our new de-

sign, with the burner covers elevated. Figure 2 is a perspective view of a range showing our new design with the burner covers closed.

That side of the range not shown in the drawing is the same as the side shown.

We claim:

The ornamental design for a range, as shown and described.
